APPARATUS FOR DISINTEGRATING CEREALS AND OTHER GRANULAR MATERIALS

Auguste Eugène François, Paris, France

Application August 9, 1939, Serial No. 289,284
In France August 16, 1938

2 Claims. (Cl. 83—9)

The present invention relates to apparatus for disintegrating, in the dry state, cereals, vegetable grains and all crystalloid grains.

The chief object of the present invention is to provide such an apparatus ensuring a more efficient and regular disintegration of the matters to be treated through simple and strong mechanical means, and modifying the physical state and the qualities of the disintegrated matters.

An essential feature of the present invention consists in exposing the matters, during, and even after, their disintegration, to the action of rays having particular properties (ultra-violet, infra-red rays).

An essential feature of the device according to the present invention consists in effecting the disintegration by means of a cylinder or drum having a continuous circular movement, of uniform or adjustable speed and providing in said cylinder or drum at least one brush capable of constantly detaching the disintegrated particles of matter treated from the abrasive inner lining of the cylinder or drum.

Other features of the present invention will result from the following detailed description of some specific embodiments thereof.

Preferred embodiments of the present invention will be hereinafter described, with reference to the accompanying drawings, given merely by way of example, and in which:

Fig. 1 is an elevational view, partly in section of a disintegrating device made according to a first embodiment of the invention;

Fig. 2 is a sectional view on the line II—II of Fig. 1;

Fig. 3 is a plan view of a disintegrating device made according to a second embodiment of the invention.

In the following description, it will be assumed that the apparatus is made for disintegrating cereals or the like.

The apparatus includes at least one cylindrical drum 1, of circular section for instance, the lateral wall of which carries, on its inner face, an abrasive lining constituted by suitable powdery matters such as flint, by a perforated metal sheet, corrugated steel or the like. The end plates, 2 and 3 of the cylindrical drum constitute a portion of said inner wall, so that the whole constitutes a cylinder closed on all sides into which the matters to be treated are introduced through one or several apertures 4 closed by suitable doors 5. The removal of the treated matters can take place, in the example shown by the drawings (Figs. 1 and 2) through the same apertures, or

other apertures (not visible on the drawings) which may be connected to a source of suction.

Drum 1 is carried by a frame 6 through the intermediary of rollers 7 bearing on said frame and which are in contact with the lateral wall of the drum, being engaged between guiding rails 8. The rollers are mounted by pairs on spindles 9 capable of rotating freely in their bearings 10 carried by frame 6.

In the example shown by Figs. 1 and 2, the drum is caused to rotate through the intermediary of a connecting rod 11 hinged at one end to a crank pin 12 mounted on the end plate 2 of the drum, while the other end of said connecting rod 11 is pivoted to a crank pin 13 mounted on a driving disc 14. This disc is keyed on a shaft 15 capable of being driven by suitable motive means, for instance through the medium of a belt 16 adapted to be engaged at will either on a driving pulley 17, in the case in which it is desired to drive the drum, or on a freely rotating pulley, adjacent to said driving pulley 17, when it is desired to stop the machine. When belt 16 is engaged on pulley 17, I obtain a continuous drive of drum 1 by the driving disc 14 and through the intermediary of connecting rod 11.

When it is desired to drive drum 1, such as above described, at an adjustable speed, I may, as shown by Fig. 3, mount on the lateral wall of said drum a toothed wheel 18 which meshes with a pinion 19 keyed on a driving shaft 20. This shaft 20 carries a pulley 21 on which is engaged a belt 22 driven by another pulley 23 at an adjustable speed and for instance through the intermediary of the following means: Pulley 23 is fixed on an intermediate shaft 24 driven by a conical pulley 25¹ associated with a conical pulley 25² of inverse arrangement, these two last mentioned pulleys being connected together by a belt 26. This belt 26 can be given an axial displacement with respect to the pair of conical pulleys 25¹ and 25² through the intermediary of a fork-shaped member 27 mounted on a sleeve 28 engaged on a threaded rod 29. In this case, it suffices to drive conical pulley 25² by means of any suitable source of power, and to adjust the position of belt 26 with respect to pulleys 25¹ and 25² for obtaining a drive of drum 1 at any desired, and adjustable speed.

Advantageously, as shown by Fig. 3, I adjoin to the adjustable speed device a second analogous device, including the opposed conical pulleys 30¹ and 30², connected together by means of belt 31. The axial position of which with respect to said pulleys can be modified through the intermediary

of sleeve 32 and threaded rod 33. In this case, I mount on the spindle of pulley 30² a driving pulley 34 driven in any suitable manner, and I connect the pair of pulleys 30¹ and 30² to the other pair of pulleys 25¹ and 25², through the intermediary of a belt 35 engaged on the pulleys keyed respectively on the spindles of conical pulleys 30¹ and 25². The synchronous rotation of threaded rods 29 and 33 can be obtained through the intermediate of a hand-wheel 36 which drives a sprocket wheel 37 around which passes a chain 38 meshing both with pinion 39¹ keyed on rod 29 and with pinion 39² keyed on rod 33.

In order to free the abrasive lining from the particles produced by the disintegrated matters and this in a continuous manner, I make use of a cylindrical brush 40 fixed on a spindle 41 the ends of which are mounted in bearings 42. The brush is supported by a plate or steel sheet 43 provided with apertures and adapted to act as a spring. This plate is fixed on the external cages 44 of ball bearings 45 freely engaged on trunnions 46 carried by the end plates 2 and 3 of drum 1, respectively. A free end of plate 43 carries rollers 47 freely journalled on the ends of their supports 48 and in contact with the inner wall of drum 1. The other end of said plate 43 carries, through the intermediate of supports 49, rollers 50 which are also in contact with the inner face of drum 1 in such manner as to roll thereon. This movement of rotation of rollers 50 is transmitted to brush 40 through the intermediate of gear wheels 51 keyed respectively on the spindle of rollers 50 and on the spindle 41 of brush 40. It follows that said brush is constantly driven in a direction opposed to the movement of rotation of drum 1, while being constantly kept in elastic contact with the abrasive lining of said drum. With such an arrangement, this lining is cleaned in a continuous manner and the disintegrated particles detached therefrom are collected by plate 43. These particles can pass through the apertures provided in said plate. Accordingly, the lining is constantly kept in a clean state and ready to ensure disintegration of the matters that are treated. Furthermore, the working of this brush makes it possible to increase the rotary speed of drum 1 since the lining is constantly freed from the disintegrated particles that have a tendency to adhere thereto, whereby this lining can constantly act, in an efficacious manner, on the matters to be treated.

Advantageously, I provide, on the end plates 2 and 3 of the drum, and more particularly on the end plate 3 opposed to that on which the driving connecting rod 11 is acting, sources of rays having particular properties, for instance sources of ultra-violet or infra-red rays. As it is

well known, these sources are generally constituted by electric lamps, for instance mercury vapour lamps in the case of ultra-violet rays, which are fed with current through the intermediary of fixed circular rings 52 and 53 which are fitted on a stirrup 54 rigid with frame 6. These rings 52, 53 cooperate with contact studs such as 54a driven by drum 1 in the course of the rotation thereof and which serve to transmit the electric current to the sources in question. Wires 55 leading respectively to circular rings 52 and 53 permit of connecting said rings to a suitable source of current. Reflectors 56 are advantageously combined with lamps 57, which constitute the sources of rays above mentioned, for directing the rays coming from these lamps toward the matters to be treated, that is to say in a direction substantially parallel to the axis of rotation of drum 1.

The system above described permits of obtaining a very satisfactory disintegration of the matter with a high mechanical efficiency. On the other hand, the presence of the sources of rays having particular properties permits of improving the physical and other properties of the matter that is treated.

In a general manner, while I have, in the above description, disclosed what I deem to be practical and efficient embodiments of the present invention it should be well understood that I do not wish to be limited thereto as there might be changes made in the arrangement, disposition and form of the parts without departing from the principle of the present invention as comprehended within the scope of the appended claims.

What I claim is:

1. An apparatus for disintegrating a matter of the type mentioned, which comprises, in combination, a frame, a cylindrical drum of circular cross section journalled about said frame, an abrasive lining on the inner surface of said drum, means for rotating said drum about its axis in said frame so that the matter present in said drum rubs against said lining, a circular brush having its axis parallel to the axis of said drum mounted inside said drum, a spindle for said brush, spring means for supporting said spindle so as to keep said brush in contact with said abrasive lining, and rollers adapted to run on the cylindrical inner wall of said drum operatively connected with said spindle for rotating said brush in a direction opposed to the direction of rotation of said drum.

2. An apparatus according to claim 1 in which the means for supporting said spindle in said drum consist of a perforated spring plate.

AUGUSTE EUGÈNE FRANÇOIS.
